United States Patent Office.

P. F. RANDOLPH, OF JERSEYVILLE, ILLINOIS.

Letters Patent No. 95,265, dated September 28, 1869.

IMPROVEMENT IN POLISHING-MACHINE.

The Schedule referred to in these Letters Patent and making part of the same.

To all whom it may concern:

Be it known that I, P. F. RANDOLPH, of Jerseyville, in the county of Jersey, and State of Illinois, have invented a new and improved Polishing-Machine; and I do hereby declare that the following is a full and exact description of the same; reference being had to the accompanying drawings, and to the letters of reference marked thereon.

This invention relates to an improved machine for grinding and polishing metallic and other surfaces, and consists mainly in the employment of a wheel having an elastic tube around the same, provided with a flat outer surface, over which passes an emery belt; also, in so constructing the machine, that by a duplication of pulleys a greater length of belting can be used in a small space, as will hereinafter more fully appear.

In the drawings—

Figure 1 is a side elevation of my invention; Figure 2 is a side elevation of the wheel A; and Figure 3 is a vertical central section through line x x in fig. 2.

X represents the foundation of the machine, which may be of any desired form, on which are located, in suitable bearings, the driving-wheel B, pulleys C, and grinding and polishing-wheel A, which latter consists of the circular clamps A¹ A², which are confined by the bolt A², and the elastic tube a, which is constructed of rubber or other suitable material, and is inflated and air-tight.

a¹ represents a flat rim, of similar material, and extending around the same. The rim a¹ may be merely a protuberance on the tube a, or attached after the manner of an elastic tire. Its object is to furnish a bearing-surface for the belt E.

The tube a is provided on its inner circumference with the projection a², which is held between the clamps A¹, and confines the hollow rim a firmly in place.

The belt E is composed of duck or leather, covered with emery, and passes over the wheel A, driving-wheel B, and pulleys C, which latter, by their arrangement, admit of a much greater length of belting than could otherwise be obtained without extending the same beyond the limits of the machine.

The operation of my invention will be readily understood. The surface to be ground or polished is pressed against the belt, over the elastic rim a of the wheel A, which, by reason of its yielding nature, admits of all parts of the surface to come in contact with the belt. It is, therefore, peculiarly adapted to grinding plowshares and other irregular surfaces.

I am aware that an inflated rim of India rubber, coated with sand, has been employed, but its construction and attachment are different from my invention.

Having thus fully described my invention,

What I claim as new, and desire to secure by Letters Patent, is—

The wheel A, consisting of the inflated tube a, rim a¹, projection a², and clamps A¹, in combination with the belt E, driving-wheel B, and pulleys C, arranged and operating substantially as described.

This specification signed and witnessed, this 12th day of December, 1868.

P. F. RANDOLPH.
